UNITED STATES PATENT OFFICE.

THOMAS SYMONDS, OF CAMDEN, NEW JERSEY.

IMPROVEMENT IN DREDGING-BUCKETS.

Specification forming part of Letters Patent No. 150,373, dated April 28, 1874; application filed April 3, 1874.

To all whom it may concern:

Be it known that I, THOMAS SYMONDS, of Camden, in the county of Camden and State of New Jersey, have invented certain new and useful Improvements in Dredging-Buckets, of which the following is a specification:

The object of this invention is to produce a dredging bucket or apparatus more especially adapted to light dredging, and when it is desired to dredge only for light objects; and it consists in a pivoted or vibrating beam, to the center of which the lowering-chain is connected, and the opening and closing chains to the outer ends thereof. The shaft or spool, with the large and small pulleys or sheaves, is suspended from the ends of said beam, and in such a manner that, when the two jaws of the bucket are wide open, the upper and lower ends of the chains are in a perfectly-straight line with the diameter of the small pulleys, to which they are firmly secured. This invention also consists in making the eyes through which the poles pass separate from the cross-head, and securing them by a pin thereto, so that they can be easily and readily connected and disconnected. The object of this is that the different parts may be easily connected and disconnected, besides being much cheaper to make than any other now in use, and dispensing with collars.

In the accompanying drawing, Figure 1 represents a front view of my dredging-bucket. Fig. 2 is a side view of it when closed. Fig. 3 is a side view of it when open. Fig. 4 is a detail view of the cross-head. Fig. 5 is a detail side view of the pulleys and guide.

In the drawing, A A' are the two jaws, which may be of any desired form or shape; and they are pivoted to the shaft B, upon which they are held by the eyes of the poles on one side and pins a, and on the other side by the eyes C, to which the opening-chains D D' are attached, and pins b. The levers E E', which are braced by braces e e', are connected at one end to the outer ends of the jaws by suitable studs and pins, and at the other to the cross-head pins F. These pins are provided with an eye, f, through which the guide-poles G G' pass, and connect with the shaft B by eyes on their ends. The pins F pass into the ends of the open cross-head h on the inside, as shown in Fig. 4. To the

center of the cross-head H a vibrating beam, I, is secured, having in its center an eye or hole, to which the hoisting and lowering chain K is attached. To the outer ends of this vibrating beam the opening-chains D D' are connected, being attached to the upper and lower sides of the small pulleys L L', which are cast in one piece with the large pulley M, having only a hub between them. To the large pulley M the closing-chain N is attached, by which the jaws are closed. The opening-chains are just long enough to form a perfectly-straight line with the diameter of the small pulleys when open, as shown in Fig. 3; and, when closed, they lap around these pulleys just one-half of the circumference, as best seen in Fig. 5.

To prevent any possibility of entangling or catching, and avoid friction, I have arranged a guide-pulley, O, on the cross-head H.

By hanging the pulleys in the manner described, the usual shaft and guides are entirely dispensed with, thereby obviating all friction, and a large amount of chain is saved.

The advantages of my present improvement are, great simplicity and cheapness of construction, and there is no possibility of entangling the chains or any part connected therewith.

The different parts can be very easily and quickly connected and disconnected for transportation, &c.

Having thus described my invention, what I claim, and desire to secure by Letters Patent, is—

1. The pivoted vibrating beam, in combination with the cross-head and dredging-bucket, substantially as described.

2. The combination of the suspended pulleys and chains with a vibrating beam and a dredging-bucket, in the manner shown, and for the purpose described.

3. The combination of jaws A, levers E, shaft B, pulleys L M, chains D K N, cross-head H, and vibrating beam I, all constructed substantially as shown, and for the purpose set forth.

In testimony that I claim the foregoing I have hereunto set my hand this 13th day of March, 1874.

THOMAS SYMONDS.
